UNITED STATES PATENT OFFICE

LE ROI E. HUTCHINGS, OF TONAWANDA, NEW YORK, ASSIGNOR TO REMINGTON RAND INC., OF BUFFALO, NEW YORK

INDEX

Application filed August 28, 1930. Serial No. 478,511.

This invention relates to a visible index in which a series of index cards are mounted in offset overlapped relation to each other on an index panel.

5 The invention is particularly adapted for use for hotel index systems but of course may be used for other purposes where its advantages are desirable.

An object of the invention is to provide a visible index card of special construction having a pocket in which room slips, or other data cards may be placed in such a manner that the index data thereon is readable at a glance.

10 The invention further comprehends the provision of a special card holder formed from a card or sheet having attaching means on one marginal portion for detachably mounting the card holder on an index panel while the remaining portion of the holder is formed with portions having cooperation with portions on a transparent strip or sheet to detachably interlock the transparent strip with the holder to form a pocket for receiving 15 a record card, the pocket opening toward the free margin of the holder.

Other features of the invention will appear in the following detailed description and claims.

20 In the accompanying drawings:

Fig. 1 is a side elevational view showing a complete index panel, a support therefor, and a series of cards in place thereon.

Fig. 2 is an elevational view of a single card.

25 Fig. 3 is a sectional view taken on line 3—3 of Fig. 2.

Fig. 4 is a fragmentary view of the transparent pocket-forming member.

Fig. 5 is an enlarged sectional view taken on line 5—5 of Fig. 2.

In Fig. 1 of the drawings there is shown an index panel 10 mounted by the arms 11 on a wall or other surface 12. The panel 10 is provided with a retaining strip 13 upon which the index cards 14 are detachably and slidably mounted. The location of the bottom card on the guide is determined by stops 15 mounted on the panel 10 adjacent the lower end of the guide 13.

Each card is identical in form so a description of one will suffice for all.

A card holder 14 has one marginal portion formed with tongues 16, the inturned portions 17 of which engage under flange portions 18 of the strip 13. The portions 18 are spaced from the surface of the panel 10 to accommodate the portions 17 of tongues 16 to provide for sliding movement of the card holders thereon. The upper portion 19 of the card holder is free and is provided with a contrasting color or shade from the record cards used, a finger notch 20 in the free edge, and slits 21 adjacent the side marginal portions thereof. A transparent pocket-forming member 22 preferably of celluloid overlies part of the upper portion 19 and is formed with reduced portions 23 at the ends adapted to be passed through and closely engage in the slits 21. Extension or ears 24 formed on the portions 23 serve to lock the member 22 in the slits 21. The bottom edge of the pocket-forming member is supported by ears 25 formed from the body of the card holder which also prevent a room slip or other record cards from slipping downwardly out of a visible position. Record cards 26 shown in Fig. 1, are held in the pockets formed by the card holder and member 22. These cards 26 have their upper edges terminating at the upper free edge of the card holder as shown in order to have the index thereon in visible position.

When the card holders are mounted on the retaining strip 13 the tongues engage 25 under the flanges 18 and the lower edge of one card holder engages the shoulders 27 of the next adjacent card so that the card holders will lie in offset overlapping relation. The free marginal portion of each card holder is visible for visibly indexing the record cards, and the distance between the shoulders 27 and the adjacent edge of the card holder determines the width of the visible margin. It will be noted that the edge of the transparent strip adjacent the free edge of the card holder is spaced from the edge of the card holder an amount substantially equal to the width of the visible margin whereby the overlying card will conceal 90 95 100

the celluloid strip. In this way the marginal portion of the record card 26 overlying the free exposed margin of the card holder may be grasped for removal, which is facilitated by the recess 20 providing a finger notch.

This card holder provides a structure in which the record cards or slips may be easily removed and replaced which is a frequent necessity in using the holders for a hotel room index, and the contrasting color between the holder and record card readily signals the position of holders from which the record slips or cards have been removed.

15 The transparent strip is easily attached or detached from the card holder and when attached is firmly interlocked with the holder without additional connecting means and the special form of both the holder and transparent slip provides an economical structure for manufacture and assembly.

What is claimed is:

1. An index card holder formed with supporting means on one marginal portion 25 adapted to engage a retaining member on an index panel and space a series of card holders in offset overlapping relation with the other marginal portion of each card holder in visible relation, and a pocket-forming member overlying one face and attached to a portion of the card holder spaced from said other marginal portion and cooperating with the card holder to receive a record card.

35 2. An index card formed with guide-engaging members adapted to slidably engage a guide member of an index panel, a transparent pocket-forming member overlying a portion of said card and provided with attaching ears, slots formed adjacent the margins of the last-mentioned portion adapted to receive said ears and means engaging the bottom edge of the transparent pocket member to form a bottom for the pocket provided between the card and pocket member.

40 3. In combination, an index panel provided with a guide member, a plurality of index cards formed with guide-engaging portions slidably mounting said cards on the panel in offset overlapped relation, a marginal portion on each card being in visible index relation, a strip on one face of each card, and means for detachably connecting the ends and one edge of the strip to the card to form a pocket between the card and strip.

45 4. In combination, an index panel provided with a guide member, a plurality of index cards formed with guide-engaging portions slidably mounting said cards on the panel in offset overlapped relation, a free visible marginal portion on each card being formed with a finger notch, a transparent pocket member mounted below the finger notch and overlying one side of said card, means for detachably connecting the pocket

member to the card at the ends and one intermediate edge, the edge adjacent the free marginal portion of said card being free and a record card supported between said pocket member and index card having a free margin overlying the free marginal portion of said index card and concealing the finger notch therein.

5. A card holder for record cards, comprising a sheet having attaching means provided on one marginal portion for detachable engagement with a support and having a finger notch formed in the opposite marginal portion, a transparent strip overlying one face of said sheet between said notch and said means, cooperating means at the ends of said strip and the adjacent portions of said sheet detachably connecting said strip to said sheet and tongues formed in said sheet overlying the edge of said strip opposite said notch, whereby said sheet and strip cooperate to form a pocket therebetween closed on three sides and open on the side adjacent said notch.

6. A card holder for record cards, comprising a sheet having attaching means provided on one marginal portion for detachable engagement with a support and having a finger notch formed in the opposite marginal portion, a pocket member overlying one face of the sheet and spaced from said other marginal portion, cooperating means on the pocket member and the sheet to detachably connect the same to form a pocket therebetween, and a record card mounted in said pocket and having a portion protruding therefrom and overlying said opposite marginal portion and the finger notch therein.
